UNITED STATES PATENT OFFICE.

AXEL G. TORST, OF MODESTO, CALIFORNIA.

CLOTHES HANGER.

Application filed August 23, 1926. Serial No. 131,058.

This invention relates to improvements in clothes hangers, and has particular reference to a device used in conjunction with a stationary support such as a tent pole, whereby 5 the apparel of a tourist or camper may be readily suspended by virtue of the construction of the device.

Another object of the invention is to provide a simple efficient device which can be 10 readily applied to the ordinary tent pole and which will securely hold in position wearing apparel from contact with the ground.

Other objects and advantages will be apparent during the course of the following 15 description.

In the accompanying drawings forming a part of this specification and in which like numerals are employed to designate like parts throughout the same,

20 Figure 1 is a perspective view of a tent showing hangers in position on the poles thereof,

Figure 2 is a side elevation of a tent pole and the hanger attached thereto, and disclosing one form of hanger,

Figure 3 is a similar view disclosing a modified form of hanger, and

Figure 4 is a side elevation on an enlarged scale showing the hanger per se.

30 In the course of camping, great inconvenience has been experienced due to the fact that oftentimes it is necessary to place wearing apparel on the ground or on articles such as boxes, trunks, etc., positioned in the tent 35 thus presenting an unsightly appearance in the interior of the same, and further utilizing unnecessary space.

To overcome this annoyance and inconvenience I have devised a simple type of 40 hanger preferably made of wire which can be readily secured to a tent pole so that wearing apparel can be neatly suspended, and the attractiveness of a camp site thereby enhanced.

45 In the accompanying drawings wherein for the purpose of illustration is shown a preferred embodiment of my invention, the numeral 5 designates a tent provided with the usual tent poles 6 which have secured thereon pintles 7. To the tent pole and its pintle there is secured my improved hanger 50 which embodies in its construction a single strand of wire including a straight portion

8 which is bent at right angles as indicated at 9 and terminates in a loop 11 adapted to straddle the pintle 7. In the length of the wire 8 I preferably twist the wire as at 12 so as to form a hook element 13, while adjacent the lower end of the wire, a loop 14 is formed which is of a substantially greater 60 diameter than the loop 11 and encircles the tent pole 6.

The wire is again crimped or bent as at 16 so as to provide a second hook 17 which is spaced from the hook 13 and lies in parallelism therewith. The wire then terminates in a bottom hook 18.

In the modified form of the invention as shown to advantage in Figure 3, the construction of the hanger is similar in every 70 respect to the preferred form shown in Figure 2 except that a longer strand of wire is utilized and instead of employing a second hook 17, the wire is twisted adjacent its end so as to provide a loop 19 and an end hook 20. 75

With this construction it will be evident that the hanger can be readily applied to the tent pole by merely sliding the loop 14 over the tent pole proper and encircling the pintle 7 by the loop 11. Thus there will be 80 presented a simple and efficient hanger which will easily and securely hold thereon various articles of wearing apparel.

It is to be understood that the forms of my invention herewith shown and described 85 are to be taken as preferred examples of the same and that various changes relative to the material, size, shape and arrangement of parts may be resorted to without departing from the spirit of the invention or the scope 90 of the subjoined claim.

Having thus described my invention, I claim:—

A hanger consisting of a straight strand of wire equipped with pole engaging means 95 comprising an enlarged loop, a loop of smaller diameter than the enlarged loop and adapted to be connected to the top of a pole, the axis of said loops being in axial alignment, and an apparel supporting means 100 formed integrally with said loop, said means comprising hook elements extending outwardly from said straight strand of wire.

In testimony whereof I affix my signature,

AXEL G. TORST.
